Inventor:

Albert Hirschmüller

UNITED STATES PATENT OFFICE.

ALBERT HIRSCHMÜLLER, OF MIESBACH, GERMANY.

SPINNING MACHINE.

Application filed August 12, 1926, Serial No. 128,869, and in Germany August 28, 1925.

The fibres used in the spinning of rope yarn may either be hard or soft. Hard fibres such as sisal, manilla and the like have thick abrupt ends which tend to project, and the fibres do not therefore lend themselves to the production of smooth polished yarn, a circumstance which lessens their value. To remedy this defect attempts have been made to cover a core of hard fibres with a layer of soft fibres, for instance tow, which can be polished so that the yarn will present a smooth surface. This is generally effected by means of a gill spinning frame wherein rib-shaped slivers of the two materials are delivered to a flyer by a shaft and pressing rollers while they are joined at an acute angle so that the covering material gets wound spirally about the core material as the latter is twisted. In this arrangement the two slivers are uniformly delivered, and any unevenness in the core, due to the fibres themselves or to the presence of extraneous particles, has a detrimental effect on the covering which thereby either becomes excessively stretched, sometimes to the breaking point, or applied too loosely to the core. In both instances the yarn will suffer in strength as well as in appearance, since the unevenly stretched materials will act separately in resisting the pull and are therefore more liable to break.

The object of the present invention is to obviate these disadvantages and to produce a cored rope yarn which, while stronger than yarn made exclusively of soft fibre, will equal the latter in appearance. With this object in view the invention consists in forming the pressing roller for the covering material with transversely extending recesses enabling the ribbon to slip in an intermittent fashion under the pull of the core so as to prevent overstraining, an arched plate being arranged so as to support and guide the two ribbons while they are being united. This arrangement enables a thin covering ribbon to be employed without risk of breakage, and a smooth and uniformly twisted yarn will be obtained. The plate is preferably pivoted and spring-supported so that it will tend to keep the yarn in uniform tension and prevent uneven winding of the bobbin from resulting in unevenness in the twist. Prolonged changes in the pull are compensated for by the provision of an additional, hand-operated brake applied to the bobbin,

so that uniformity of twist can at all times be ensured.

Fig. 1 of the accompanying drawings represents a sectional side view of the arrangement, and

Fig. 2, a front view of the same.

The core material passes in known manner as a ribbon-shaped sliver between feed rollers *a* and over the gill bars *b* to a delivery shaft *c* which also serves as a drawing roller and for this purpose co-operates with a pressing roller *d*. From the shaft *c* the ribbon goes to a flyer *e* whereby it is twisted and at the same time wound on a bobbin *f*. The shaft *c* also supplies a ribbon of covering material which is controlled by a pressing roller *g* arranged coaxially with the roller *d*. Immediately in front of the shaft *c* there is, according to the invention, an arched plate *h* which supports and guides the two slivers and causes the covering material to be wound uniformly about the core as the latter is twisted by the flyer. The slivers meet at an acute angle and the covering material winds in a steep spiral round the core and produces a firm, long-stapled yarn.

As the covering material is wound over the circumference of the core, it is necessary to feed it at greater speed than the core material. For this purpose, the covering material is led, in known manner, over an enlarged portion *c'* of the delivery shaft. According to the invention the enlargement of this portion is modified so that the core exerts sufficient pull on the covering material to prevent accidental slackening. To prevent overstraining of the covering material, the roller *g* is formed with transversely extending recesses *i* which allow the materials to slip in an intermittent fashion. The outer edges of the roller are left intact for continual engagement with the delivery shaft. As each fresh turn of the covering ribbon overlaps the previous one on the core, one side of the ribbon has a larger circumference to cover than the other and therefore requires greater feed. To allow for such greater feed, the recesses *i* are tapered, as shown in Fig. 2, so that the materials can slip more at one side of the ribbon than at the other.

The same effect may be obtained by making the roller *g* and the shaft portion *c'* conical instead of cylindrical. Evidently the

recesses can be made in the shaft portion lower end of the plate *h*, of a soft elastic *c¹* instead of in the roller *g*.

Irregular pull on the yarn, which would detrimentally affect the twisting process on the plate *h*, is compensated for by arranging the plate on a pivot *k* and supporting it by a spring *l* which maintains regular tension. The spring effect may be adjustable. More durable changes in the pull may be compensated for by means of an additional bobbin brake *m* arranged so that it can be adjusted by hand according to need. The usual automatic brake may be employed at the same time so as to meet relaxed resistance due to the growth of the bobbin. Naturally the brake *m* may also be adapted to act automatically for the same purpose. The additional brake has the advantage that the device can easily be adjusted for changes in the nature of the material, for instance from long to short fibre and from coarse to fine yarn or vice versa. In the case of long fibres, for instance, less twist and therefore more bobbin resistance is required than in the case of short ones.

The plate *h* also serves as a means for polishing the yarn. In the first place the core material is evened out by being passed through a trumpet mouth *n* at the upper end of the plate. Projecting fibre ends will be kept down by the trumpet while they are being twisted into the core by adjacent fibres. The narrow end of the trumpet is preferably rendered elastic for instance by forming the upper half into a separate hinged shell *o* which is held by spring pressure against the rigid lower half or against the enclosed sliver. While the covering material is led over the plate in the plane of the pressing roller *g*, the core material is led in at an angle to said plane, the plate *h* being formed with a raised edge *p* whereby the core is guided. The edge and the plate itself form together a guide surface with which the yarn contacts to the extent of at least one quarter of its circumference, and the plate will therefore have a considerable polishing effect on the yarn. As the covering ribbon remains in the plane of its pressing roller, any fibres which adhere to and follow the roller will, when stripped off, return to the ribbon.

To further the polishing of the yarn, means are provided, for instance a dripping nozzle *g*, for moistening the yarn at the point where the covering is applied to the core. Moistened rollers may be used for the same purpose. This surface moistening of the yarn allows a quick drying of the same so that it can be wound and kept on the bobbins without risk of growing mouldy. To ensure proper drying, hot air may be passed across the yarn on its way to the bobbin. Still further polish may be applied to the yarn by the provision, at the

lower end of the plate *h*, of a soft elastic polishing element *r* of felt or the like arranged so as to press the yarn against the plate. As the twisting and polishing of the yarn takes place at the same time, the direction of the polishing will be along the fibres, and loose fibre ends will therefore be more effectively smoothed down than when the polishing takes place in the axial direction

75

By this simultaneous twisting and covering of the core and polishing of the yarn while the materials pass from the delivery shaft to the sliver, a considerable improvement in the production of rope yarn is 80 achieved.

I claim:

1. In a machine for spinning cored rope yarn, the combination with a delivery shaft and with two pressing rollers which cooperate with said shaft for supplying ribbon-shaped core and covering materials to a flyer spindle, of an arched plate arranged so as to support and guide the materials while they are being united, the pressing roller 90 for the covering material being formed with transversely extending recesses enabling the materials to slip under the pull of the core.

2. A structure according to claim 1 wherein the roller recesses taper so as to allow the 95 covering ribbon greater slip at one side of the roller than at the other, substantially as and for the purpose set forth.

3. A structure according to claim 1 wherein the plate is pivoted and spring-supported 100 so as to keep the yarn in uniform tension.

4. The structure claimed in claim 1 and a trumpet mouth arranged so as to receive the core material from the delivery shaft and feed it on to the plate, the narrow end 105 of said trumpet mouth being resilient.

5. A structure according to claim 1 wherein the plate is arranged so as to maintain the covering material in the plane of its pressing roller while the core material is 110 fed at an angle thereto, the plate being formed with a raised edge along which the core material is guided.

6. The structure claimed in claim 1 including means for moistening the yarn on 115 the plate, and means on said plate for holding a polishing element against the moistened yarn.

7. The structure claimed in claim 1 including means for moistening the yarn on 120 the plate, means on said plate for holding a polishing element against the moistened yarn, and means for drying the yarn under the influence of hot air.

8. The structure claimed in claim 1 including a bobbin for taking up the yarn from the flyer and means for braking said bobbin.

ALBERT HIRSCHMÜLLER.
